UNITED STATES PATENT OFFICE.

JOHN A. SLOAN, OF TRENTON, NEW JERSEY.

DESIGN FOR TILING.

SPECIFICATION forming part of Design No. 36,920, dated May 17, 1904.

Application filed April 22, 1904. Serial No. 204,485. Term of patent 14 years.

To all whom it may concern:

Be it known that I, JOHN A. SLOAN, a citizen of the United States, residing at Trenton, in the county of Mercer and State of New Jersey, 5 have invented a new, original, and ornamental Design for Tiling, of which the following is a specification, reference being had to the accompanying drawing, forming part thereof.

The figure is a plan view of a tiling, showing my new design.

What I claim as new, and desire to secure by Letters Patent, is—
The ornamental design for tiling, as shown.

JOHN A. SLOAN.
